DESIGN FOR AN INSECTICIDE SPRAYING DEVICE

George Hettinger, East Rutherford, N. J., assignor
to Du-La Manufacturing Company, a corpora-
tion of New York

Application July 1, 1938, Serial No. 78,208

Term of patent 3½ years

To all whom it may concern:

Be it known that I, George Hettinger, a citizen of the United States of America, residing at East Rutherford, in the county of Bergen and State of New Jersey, have invented a new, original, and ornamental Design for Insecticide Spraying Devices, of which the following is a specification, reference being had to the accompanying drawing, forming a part thereof.

The figure is a perspective view of an insecticide spraying device showing my new design.

I claim:

The ornamental design for an insecticide spraying device, as shown.

GEORGE HETTINGER.
